UNITED STATES PATENT OFFICE.

HUGH L. CAMPBELL, OF NASHVILLE, TENNESSEE.

TIP FOR LACES.

Application filed July 19, 1922. Serial No. 576,051.

To all whom it may concern:

Be it known that I, HUGH L. CAMPBELL, a citizen of the United States, residing at Nashville, in the county of Davidson and 5 State of Tennessee, have invented certain new and useful Improvements in Tips for Laces, of which the following is a specification.

This invention has reference to tips for 10 shoe laces and the like and particularly to a metal tip of improved construction.

An essential object of the invention is to provide a tip which will not pull off, or become loose, means being provided for hooking 15 the tip securely to the lace.

A further object of the invention is to provide a metal tip of the above mentioned character that is simple in construction, strong and durable, and which it is believed 20 may be manufactured at a reasonably low cost.

Various other objects and advantages of the invention will become apparent from the following description.

25 In the drawing:

Figure 1 is a perspective view of a lace-end with the improved tip applied thereto.

Figure 2 is an enlarged view, in longitudinal section, of the lace-end showing the 30 manner in which the tip is secured thereto.

Figure 3 is a vertical cross section along line 3—3 of Figure 2, and

Figure 4 is a plan view of the blank from which the tip is formed.

35 Describing the invention in detail 10 designates a blank of metal or other suitable material from which the tip is formed.

This blank comprises a flat body portion of rectangular configuration from one end 40 of which projects a narrow tongue 11 in line with the longitudinal axis of the blank. Tongue 11 is inserted thru a slot or opening 12 provided in lace 13 and is bent at

point indicated respectively by dotted lines 14 and 15 to provide a hook for securing 45 the tip to the lace as will be clearly understood from the consideration of Figure 2.

The sides 16 and 17 of body portion 10 are bent up around the tip-end of the lace, as shown in Figure 3 to provide a ferrule 50 for the lace which strengthens and reinforces the same at its end. The ferrule may be pressed round or flat as desired and the adjacent edges of the same over lie the end of tongue 11 which is thereby prevented 55 from working loose. It will thus be seen that the tip is fastened to the lace in such a secure manner that it cannot work loose and pull off as is frequently the case with the type of tips now in common use. The 60 provision of a locking tongue or pin enables the ferrule portion of the tip to obtain a firmer grip on the lace which is pinched therebetween. The tip is attachable to the lace by pressing the sides together in the usual manner and hence may be quickly and readily applied to the lace. 65

From the foregoing it is believed that the advantages and novel features of the invention can be readily understood and that 70 further detailed description thereof is not required.

What is claimed is:

A shoe lace tip including in combination with a shoe lace provided with a transverse slot adjacent its end, a normally flat ferrule portion, a substantially blunt tongue integral with said ferrule portion and adapted to be inserted into said slot and bent to lie parallel with the lace, and said 75 ferrule portion being adapted to be bent around the end portion of the lace and said tongue substantially as described.

In testimony whereof I affix my signature.

HUGH L. CAMPBELL.
